MULTIPLE LEVER TOOL

Willis F. Tibbets, Reading, Mass., assignor to
 H. K. Porter, Inc., Somerville, Mass., a corpora-
 tion of Massachusetts

Application November 5, 1949, Serial No. 125,814

6 Claims. (Cl. 30--193)

1

This invention relates to multiple lever tools and has a particular application to tools of the type known as bolt clippers or rod cutters for severing metal rods. In general it may be said that the object of the invention is to provide a practical construction for a hand operated tool wherein a uniform force, manually exerted on the handles, will be translated into a variable force at the jaws, varying as does the resistance of the work at the point of cutting. Although the construction may be applied to tools of capacities corresponding to those now in use, an important feature is that it permits the construction of a tool for cutting work beyond such capacities.

My invention will be well understood by reference to the following description of the illustrative embodiment thereof shown by way of example in the accompanying drawing, wherein:

Fig. 1 is a side elevation of the tool;

Fig. 2 is an enlarged section of a portion thereof, with parts broken away;

Fig. 3 is an edge view as seen from above in Fig. 2;

Fig. 4 is a section on the line 4--4 of Fig. 3; and

Fig. 5 is a view similar to Fig. 2 showing the parts in open position.

In the tool illustrated as exemplary of the invention I have shown by way of example a cutter-head of the type common in present-day bolt clippers so-called, as seen in Fig. 1. It comprises two jaw levers 10-r and 10-l, pivoted on the parallel pivot bolts 12 carried by plates 14 and providing forwardly of these pivots the jaws proper having the cutting edges 16, while the rearwardly projecting portions of the levers constitute the jaw tails 18 by means of which the jaws are operated. Conventional means not illustrated are provided for connecting the two head levers and cause them to move through equal and opposite angles when the tails are spread apart from the position in Fig. 1 to close the jaws, or brought back to open them.

When a rod is severed by a cutter of this type the edges indent and plastically deform the metal. As the jaws sink deeper and deeper into the work the resistance increases rapidly. Finally as the jaws draw near the diameter, exerting a wedging pressure longitudinally of the rod on the sides of the indentation, the remaining connecting neck of metal between them (which may be of substantial thickness) fails under tension. The rod is simply torn apart and if one of the pieces is small it will be projected to a distance with a

2

considerable velocity. As this occurs the resistance drops sharply.

It will be noted that in Fig. 1 of the drawing showing the tool in closed position the edges of the jaw 16 are shown spaced apart as it is unnecessary and undesirable to provide for movement bringing them into actual contact because the work is completed before they reach such a position.

10 In the conventional bolt clipper in common use a head such as above described is operated by means of two bent handle levers, as shown for example in patent to Lindsay 146,829. These bent levers forming handles are pivoted intermediate of their ends to the jaw tails and have short arms connected to one another adjacent the jaw tail pivots. These two arms may be considered as a toggle which becomes straighter as the jaws are closed. The increase in mechanical advantage of a toggle is theoretically infinite, but for various reasons the toggle is not brought close to dead center position. Thus, while in general the mechanical advantage increases as the tool closes, it is not proportional to the resistance of the work and a heavy peak load is encountered which is taxing on the operator. A heavy duty tool of this type, as presently constructed, having a nominal capacity for cutting rods $\frac{5}{8}$ " in diameter, is 42 inches long and weighs about twenty pounds. It is not to be wielded by weaklings. This is about the limit for a hand-operated tool of this type when we consider that the advantage of such a tool is that it can be operated by hand and rapidly as compared, for example, with a hydraulically actuated mechanism. The tool herein illustrated as an example of my invention is one designed to cut rods $\frac{3}{4}$ " in diameter. As compared with a $\frac{5}{8}$ " rod this represents an increase in load of about 50%, which could not be practically handled by existing tools unless some such means as a winch were utilized for operating the handles.

45 Referring now to the drawings and particularly Figs. 1 and 2, the tool is operated from two long handle levers 20-r and 20-l, pivoted together at their distal ends on center a. The jaws may be carried from the handle levers by means of radius links 22 extending from center a and joined to the jaw tails 18 on pivots b. Conveniently from this same pivot b extend connecting rods 24 pivoted on the center b and having their proximal ends pivoted at center c to levers 26 which swing about fixed centers d on the handles. The levers 26 are extended inwardly of the pivots d and 50 connected to each other by a central pivot e. This

connection on the pivot *e* provides for equal and opposite movement of the four bar linkages connecting centers *a*, *b*, *c*, *d*.

The pair of radius links *22*, pair of connecting rods *24* and pair of levers *26* just described are substantially duplicates on opposite sides of the center line, differing slightly when viewed in Fig. 2 because they are right and left hand. It would have been merely prolix and confusing to use different reference numerals but in Fig. 4, where discrimination is helpful, I have added in parentheses to certain numerals the letter *l* for those parts associated with handle lever *20-l* and the letter *r* for those associated with handle lever *20-r*.

In the mechanical construction shown the two handle levers are bifurcated at least at their distal portions and the arms of each lever are brought together and the four arms nested in alternating relation on the pivot *a*, as best seen in Fig. 4. Similarly, each of the radius links *22* may be double and disposed at either side of the jaw tail at the pivot *b*. The levers *26* are likewise double and nested at the pivot *e* and embrace at their outer or distal ends the eyes of eye-bolts *28* forming one end of the connecting rod *24*, while the other end of the connecting rod is a bolt *30* having a terminal shackle which, as seen at the right of Fig. 4, embraces the jaw tail *18*, and is overlaid by the radius links *22*. These two bolts *28* and *30* are of right and left thread and joined by a turnbuckle *32*. The operation of this turnbuckle permits the length of the connecting rods to be adjusted to compensate for removal of metal at the jaws *16* incidental to resharpening of the tool.

In the example of the invention illustrated a single pivot *b* connects the jaw tails, the radius links *22*, and the connecting rods *24*, and this is believed to be the preferable construction. The extent of the movements would be slightly different, but the mechanical arrangement would be substantially the same if two adjacent points of connection were provided, one of the parts being connected directly to the two others and forming a rigid connection between them. For instance, the connecting rod *24* might be connected to link *22* inwardly of pivot *b* or to the jaw lever *18* distally of that pivot.

The linkages may be covered at the sides of the tool by channel-shaped sheet metal covers *34* fitting over the outside portions of the distal ends of the handles. Their distal ends may be secured by pivot *b* and their flanges may have indented bosses *36* (Fig. 1) at their proximal ends which snap into grooves *38* on the sides of the handles and slide therein when the tool is operated.

I have described the mechanical arrangement shown without any particular attention to its dimensions. In general the links *ab* and *cd* are not parallel cranks. The design of the parts to permit attainment of the objects of the invention may be effected in accordance with the following principles. Using a chosen jaw lever construction we can, by exerting direct pressure on the backs of the jaws against a piece of work representing the normal load which the tool is to carry, determine the force required for successive increments of jaw movement measured in distances perpendicular to the center line or in cutting edge angle. These results may be translated mathematically into figures showing the load at the jaw tail for these angles and the corresponding positions of the jaw tail measured

perpendicularly to the center. The relation of the load to the travel of the jaw tail may be plotted as a curve and the area under the curve determined for successive increments. On an arc representing the travel of the hand grip of the tool, positions may be laid out such that travel of the handle from point to point under a uniform force will give the same increments of work as those for equal jaw tail travel increments. These handle positions may then be used as a basis for the graphical determination of the dimensions of the links.

The mechanical advantage is varied and the parts are so correlated that the varying resistance of the work is overcome by a uniform force exerted at the handles. It should be noted that all the joints are simple pivots that is, rotary joints at a fixed point without any sliding connection which permit a construction of adequate strength and one easily made and free-working.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A tool of the class described comprising in combination a pair of jaw levers and means for swingingly mounting them in opposition to provide a pair of work engaging jaws and a pair of tails, the relative movements of which latter effect opening and closing movements of the jaws, a pair of handles pivoted together, radius links pivotally connected to the jaw tails and handles for supporting the former from the latter, levers pivoted between their ends on the handles remote from the pivotal center of the latter and having inner ends pivotally joined to enforce equal and opposite movement thereof when the handles are moved, and connecting rods extending from points in the levers remote from their pivots on the handles and operatively connected to enforce movement of the joint between the jaw tails and the radius links.
2. A tool of the class described having swinging jaw levers mounted in opposition to provide a pair of work-engaging jaws and a pair of tails and mechanism for operating the jaw tails comprising two four-bar linkages, the elements of a first pair of corresponding links of the two linkages being pivoted together and extended to provide handles, the elements of a second pair of corresponding links being pivoted to the first links and supporting the jaw tails and the elements of a third pair of corresponding links being pivoted to the first links and also being extended and pivoted together to enforce correlated movement of the two linkages when the handles are operated, the elements of a fourth pair of corresponding links connecting the second and third in nonparallel relation, providing on increments of handle grip travel consequent on a uniform force exerted thereon effective equal increments of jaw tail travel throughout the major portion of the stroke of the jaws under load.
3. A tool as defined in claim 2, wherein the

said fourth links are of adjustably variable length.

4. A cutter for metal rods comprising a pair of jaw levers pivoted together to provide a pair of jaw tails and a pair of opposed wedge-shaped jaws for indenting and finally disrupting the rod, driven links which carry the jaw tails, driving links constituting handles pivoted together at their distal ends, pairs of cooperating links which constitute the connection between said driven links and driving links and which are connected thereto by simple pivots, there being also a simple pivot connection between the elements of a pair, all the links forming a system expanding and collapsing symmetrically about the center line on operation of the handles, the cooperating links on movement of the handles from point to point under a uniform force enforcing movement of the jaws through proportional distances with varying mechanical advantage corresponding to the varying resistance to indentation of the work.

5. A portable manually operable tool of the multiple lever type for cutting rod comprising a pair of swinging jaw levers having wedge-shaped jaws which indent the work pivoted together at their distal ends and pairs of intermediate links constituting the means providing for the mutual support between the jaw levers and handles reciprocally and which are connected thereto and to one another by simple pivots, there being also a simple pivot between the elements of a pair, the handles and intermediate links being by such connections integrated in a self-sufficient link system expanding and collapsing symmetrically about the center

line on operation of the handles, the intermediate links on movement of the handles from point to point under a uniform force enforcing movement of the jaws through proportional distances with varying mechanical advantage corresponding to the varying resistance to indentation of the work.

6. A portable manually operable tool of the multiple lever type comprising a pair of swinging jaw levers having wedge-shaped jaws which indent the work and then disrupt it, a pair of operating handles pivoted together at their distal end, a pair of links forming levers of the first class pivoted together at one end and each at an intermediate point to the respective handle levers, connecting links pivoted to the other ends of the lever-forming links and to the jaw levers, and means providing for mutual support between the distal ends of the handles and the jaw levers, the links providing on movement of the handles from point to point under a uniform force enforcing movement of the jaws through proportional distances with varying mechanical advantage corresponding to the varying resistance to indentation of the work.
